UNITED STATES PATENT OFFICE.

AMOS L. KNIGHT, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA.

FLUID-PRESSURE APPARATUS.

1,300,281.

Specification of Letters Patent. Patented Apr. 15, 1919.

Application filed August 29, 1917. Serial No. 188,780.

To all whom it may concern:

Be it known that I, AMOS L. KNIGHT, a citizen of the United States, and a resident of Philadelphia, county of Philadelphia, State of Pennsylvania, have invented certain new and useful Improvements in Fluid-Pressure Apparatus; and I do hereby declare the following to be a full, clear, and exact description of the same, reference being had to the accompanying drawings forming a part of this specification and to the characters of reference marked thereon.

My invention relates to jointed apparatus provided with a plurality of fluid pressure containing cavities or ducts intersected by or in communication with a joint between members of the apparatus and has for its principal object to provide such apparatus with means whereby fluid leakage from one of said cavities through the joint is controlled and directed in such manner as to prevent it from reaching another of said cavities or ducts to cause injury to or an improper functioning of the apparatus. More specifically the invention relates to water-cooled molding apparatus for the production of typemetal elements of printing forms and has for its main object in such a structure to control leakage from the water conducting cavities or channels where the latter intersect joints between certain of the mold members and prevent such leakage from reaching the casting cavity where it would injure the mold or interfere with its producing a proper product. The invention is of especial importance in connection with such apparatus embodying joints which, due to the requirements of the situation, cannot be firmly clamped tight, notably in connection with joints between members one of which is movable relatively to the other. This feature of the invention will be more fully pointed out and other objects thereof will appear in connection with the following description of the embodiment shown in the drawings in which—

Figure 1 is a plan view of a mold for producing typemetal elements of printing forms,

Fig. 2 is a sectional view thereof substantially on the line 2—2 of Fig. 1,

Fig. 3 is a bottom plan of the rear type

block and the lower member of the front type block, and

Fig. 4 is a perspective of various parts of the mold unassembled, this view being designed to show particularly the arrangement of communicating water-cooling channels in the mold.

The mold illustrated is in its general characteristics similar to the printers' strip material mold disclosed in United States Patent No. 1,222,415, dated April 10th, 1917; and because of such disclosure and the fact that the mold is well known commercially, a detailed description thereof is not necessary herein, nor is it necessary to show or describe operating mechanism or stops for the mold blade, means for the injection of molten metal into the mold cavity, and like mechanisms, especially as such mechanisms may correspond substantially with mechanisms found in machines manufactured by the Lanston Monotype Machine Co., which have been in extensive use for many years.

Referring to the accompanying drawings, the base 3 of the mold is provided with a suitable nozzle seat 20 for the reception of a nozzle for the proper injection of molten metal into the mold cavity. Said base 3 holds the rear type block 8 and the forward type block consisting of the upper member 9 and the lower member 10, in a channel extending longitudinally of the mold blade 27 and formed by the upward extensions 4 of the base block. The bottom edge of the blade is slidable on the base block 3 and the liner or point block 14^b, the sides work in contact with the type blocks 8, 9 and 10, and the top works in contact with the point block 14^a and the matrix or its equivalent. The holding device for the matrix is secured by the screw 26 shown in Figs. 1 and 2; the hole for this screw in the type block 8 being shown at 26^a in Fig. 4. The mold blade 27 and the point blocks 14^a and 14^b are of a thickness corresponding to the point size of the element to be cast. The point blocks are held between the type blocks and the latter fastened together by the bolts 11, bolt holes 11^a for which are provided in the type block 9, 10, the point blocks 14^a and 14^b and the type block 8.

The type blocks are positioned laterally

with the mold blade central over the nozzle opening 20 by the packing plate 17 of suitable thickness; and the type block 8 is secured rigidly to the base by the horizontal 5 screws 4^a, the holes for which in the base 3 are indicated by the character 4^b in Fig. 4; and by the vertical screw 4^c, the hole for which in the base is indicated by 4^d. It will be seen that the rear type block 8 is rigidly 10 secured to the base plate 3 and that the two type blocks are firmly secured together at one end only of the mold cavity. The front type block 9, 10 is secured to the base 3 by a single screw 9^a, the hole for which in the 15 base block is indicated in Fig. 4 by 9^b. Tie bars 5 secured to the extensions 4 by bolts 5¹ are provided.

The type block 9, 10 is provided with a triangular vent opening 12 which gradually 20 enlarges toward the discharge end of the mold; and this opening is conveniently produced as shown, by constructing the block in two parts, the lower member, or part 10 being grooved in the form of the vent opening 25 and the upper part being secured to the lower part with the bottom wall of said upper part covering the groove. In this opening a pusher 28, triangular in section to fit 30 said opening, is adapted to slide, said pusher being loosely secured to the mold blade 27 by a lug 28^a thereon (Fig. 1) which seats in a rectangular hole in the blade. The two type block parts are secured together by the horizontal screws 10^a, the holes for which 35 are indicated by 10^b in Fig. 4; by the downwardly extending vertical screw 10^c the holes for which are indicated by 10^d; and by the upwardly extending screws 10^e the holes for which are indicated in Fig. 3 by 10^f.

40 The pressure screw 18 passing through the front wall 4 of the base block 3 bears at its inner end against the front type block and is operated by an arm 19 adapted to be connected with a suitable part of the machine 45 and operating in timed relation to the casting and blade moving operations of the machine to periodically place pressure upon and remove it from the front type block near the discharge end thereof.

50 The extension 3^a of the base is adapted to support the gate severing device (not shown).

The type blocks are vertically grooved slightly at 8^a and 8^b respectively such 55 grooves being in line with the forward screw hole 11^a so as to lead lubricating medium to both sides of the mold blade; the tie bar 5 above these grooves is provided with a hole 5^a leading thereto and a groove 5^b for receiving the lubricant and conducting it to 60 said hole 5^a.

The water cooling channels or cavities 65 may be traced most conveniently in Fig. 4. The entrance and exit apertures 20^a and 51 respectively are in registry or alinement

with supply and discharge apertures in the machine base when the mold is properly positioned and secured for operation. Upon entering through the aperture 20^a, the water is conducted upwardly through the channel 70 21, then horizontally through channels 22 and 23 to the aperture 24 in the upper surface of the base block 3. The water enters the block 10 through the aperture 25 (see Fig. 3) whence it is conducted upwardly to 75 the channel 26 connecting with the longitudinal channel 27, then through channel 29 to the aperture 30 alined with the aperture 31 in the upper block 9. With the aperture 31 is connected upwardly extending channel 80 32, leading to horizontal channel 33, thence to channels 34 and 35 to aperture 36 in the side of block 9. From this aperture the cooling medium traverses the hole 37 in the point block 14^a and entering through aperture 38 in type block 8 traverses channels 39, 40, 41, 42, 43 and 44 in said block 8 finding exit through aperture 45 in the lower surface of the block, whence, after passing the joint between the block 8 and the base 3, it 90 enters the block 3 through aperture 46 in the upper surface thereof and traverses channels 47, 48, 49 and 50 finally discharging through aperture 51 in the bottom surface of block 3, said discharge aperture being adapted to be in alinement or registry with a suitable discharge conduit in the mold supporting part of the type casting machine to which the mold is adapted to be secured by means of a screw inserted in slanting hole 100 52 (Fig. 1).

The joint between the machine base and the mold base block 3, in proximity to the entrance aperture 20^a and the discharge aperture 51, is a tight joint because the fastening screw through hole 52 is between and near to said apertures. The joint between the lower and upper members of type block 9, 10 is also a tight one in proximity to the apertures 30 and 31 because a fastening 110 screw 10^e is on each side of said apertures. Likewise the joints between the type blocks 8, 9 and 10 and the point block 14^a are tight, the screws 11 traversing the holes 11^a being located near to and on each side of the 115 apertures 36, 37 and 38 in the type block 9, 10, the point block 14^a and the type block 8 respectively.

The joints between the type blocks and the base block in proximity to the alined openings 24 in the base block 3 and 25 in the type block member 10, and 46 in the base block 3 and 45 in the type block 8 are not so tight as those joints just referred to because the type blocks are fastened vertically to the base 125 block each by a single screw located at one side of the said alined openings—the screw 9^a traversing hole 9^b to secure the type block 10 and the screw 4^c traversing the hole 4^d to secure type block 8. The ends of the type 130

blocks toward the discharge end of the mold are not secured together nor to the base block; moreover, the action of the clamping screw 18 causes a movement relatively to the 5 base block, particularly of the front type block at said discharge end and consequently in proximity to the alined cavities. The rear type block is permitted to move slightly near its discharge end because of the taper given 10 to the packing piece 17 at 17^a (Fig. 1) such movement being adapted particularly to take care of unequal expansion of the various mold parts during operation. Because of 15 this movement of one of the members constituting the joint and the fact that the alined apertures of the water cooling system are between the fastening screws and the movable discharge ends of the type blocks, a reliably tight joint is difficult to obtain, particularly 20 when, as sometimes happens, typemetal is accidentally lodged under the loose, discharge ends of the type blocks, or between them and the base block. Leakage of cooling water is liable to occur through and along the joint, 25 and is particularly detrimental when it reaches the mold cavity into which molten metal is introduced. Such a possibility has heretofore always been present because the mold cavity is located at the forward end of 30 the mold blade between the two type blocks and the joint referred to is between members forming the cavity. Leakage through the joint, which reaches the mold cavity has, as will readily be appreciated by those skilled 35 in the art, a detrimental effect not only upon the mold cavity walls but tends to produce explosive conditions when molten metal is introduced.

One of the objects of the present invention, 40 as hereinbefore stated, is to control such leakage, and this is preferably accomplished, in the embodiment of the invention illustrated, by providing a leakage intercepting groove 53 in the face of one of the members forming 45 the joint, for instance, the type block 9, 10 for one joint and the type block 8 for the other joint, said groove being annular to surround completely the alined apertures 24, 25 for one joint and 45, 46 for the other and being each tapped by a leading-off groove 54, 50 to drain or lead away any leakage from the alined apertures, preferably, as shown to one side of the type block, so that it may discharge into the channels 55 provided in the 55 base block in proximity to the upright extensions 4 and communicating with the atmosphere.

Obviously the form of the controlling grooves is not of importance nor is their particular location, save that they must intersect the joint around the intersection of the fluid pressure ducts and joint or lie between the fluid pressure ducts and other ducts, cavities or ports which would be injuriously affected by leakage and that they shall offer a

passage of least resistance for the free discharge of the leakage.

I claim:

1. A typographic mechanism embodying members assembled with faces in contact 70 whereby a joint is formed between said faces, said members being provided with alined fluid cavities, the cavity in each member extending through the face thereof, and with a third cavity adapted to contain a 75 fluid independent of that of the alined cavities, said third cavity also extending into communication with said joint, and said members also being provided with means, located in the joint between said alined 80 cavities and said third cavity, to direct away from said third cavity fluid escaping through said joint from said alined cavities.

2. A fluid-cooled typographic mold comprising a base block, a type block mounted thereon, said blocks being provided with a cooling fluid duct intersecting the joint between said blocks, said blocks providing a mold cavity in communication with said joint and adapted to receive molten type metal, and means in the joint intermediate the said duct and the said cavity to direct away from said mold cavity cooling fluid escaping through said joint from said duct. 85

3. A fluid-cooled typographic mold comprising a base block, type blocks secured together in spaced relation and mounted on the base block to form a mold cavity between said blocks, adapted to receive molten 100 type metal, said base block and said type blocks being provided with a cooling fluid duct intersecting the joint between said base block and each of said type blocks, and said blocks being provided with means intermediate the ducts and the mold cavity to direct away from said mold cavity cooling fluid escaping through said joints from each of said cooling-fluid ducts. 105

4. A fluid-cooled typographic mold comprising base and type blocks, means for securing said blocks together to form a mold cavity adapted to receive molten type metal, said securing means being located at one side of said mold cavity, said blocks 115 being provided with a cooling fluid duct intersecting the joint between said blocks, and a groove in the said joint intermediate the said duct and the said mold cavity to direct away from said mold cavity cooling 120 fluid escaping through said joint from said duct.

5. A fluid-cooled mold for strip elements of a printing form, comprising a base block, type blocks, a mold blade mounted to work 125 between said type blocks and upon said base block, said blocks and blade forming a mold cavity, means for securing said type blocks together and to said base block at one end of said mold cavity whereby the type blocks 130

are movable relatively to the base block at the other end of said cavity, said base block and said type blocks being provided with cooling-fluid ducts intersecting the joints between said base block and each of said type blocks at a point between the mold cavity and the means for securing the type

block to the base block, and a groove in the said joints intermediate the mold cavity and each of said ducts to direct away from the said mold cavity cooling fluid escaping through said joints from said ducts.

AMOS L. KNIGHT.
